16 Claims. (Cl. 241—153)

This application is a continuation of U.S. patent ap-
plication Serial No. 260,153, filed February 21, 1963,
now abandoned.

The invention relates to continuously operating vibrat-
ing or oscillating mills which are resiliently mounted to
allow free displacement thereof and which are forced to
describe gyratory vibrations by a suitable vibratory gen-
erator.

Vibrating mills are known in which two milling boxes,
lying one upon another or side by side, are rigidly as-
sociated to provide a screening system that is secured to
a base by supporting springs. The required vibratory
motions are produced by a generator of centrifugal forces
arranged at the center of gravity of the system, the ampli-
tude of the oscillations being dependent upon the magni-
tude of the centrifugal force generated.

There are also known oscillatory mills that consist of
two symmetrical milling systems of equal size. In this
case one system is secured to a base by supporting springs
and is resiliently connected to the second system in such
a way that both systems are capable of describing circular
oscillations which are in phase displacement to each other
by 180°. The vibrating means positioned in a central
tube is rigidly connected with one of the two systems.

In such known oscillatory mills the material to be
milled traverses the milling boxes in a horizontal direc-
tion said, in the case of milling boxes positioned one above
the other, it is always caused to issue into the next box
beneath. The discharge openings of the upper milling
box are connected by means of flexible hoses with the
inlet openings of the lower box. Thus, in the case of
milling boxes that lie side by side, there are always mill-
ings groups connected in parallel. The total length of
all the milling boxes can be utilized only partially as a
milling path. The excessive number of flexible hoses
increases the number of possible leakage points. The
milling boxes being rigidly connected with one another
are not interchangeable or are interchangeable only if
small tolerances are permitted in the construction thereof.
But even in cases such as this, such interchange can be
quite expensive; the openings and connecting flanges must
also be interchangeable. The boxes are therefore pro-
vided with means to protect them against wear and tear
which greatly increases the weight of the oscillating parts.

The adjustment of the spring elements in the known
vibratory mills has been found, in practice, to be very
troublesome. The resiliently supported masses are so
great as to require a large spring volume. Also, the sub-
sequent installation of a cooling arrangement capable of
directly cooling the walls of the boxes that contact the
material undergoing milling, involves many difficulties.
For this reason the applicability is largely confined to the
milling of materials that are not affected by heat.

2

The object of the present invention is the avoidance of
the drawbacks that attend the use of known vibratory
mills. A further object of the invention is the provision
of improved mills of the aforesaid type. This particular
improvement lies in the fact that milling boxes have been
devised that are cylindrical in cross section and are held
with their front ends in side pieces that are rigidly con-
nected with one another. These side pieces are formed
in such a way as to jointly enclose the front ends of the
milling boxes. By a suitable subdivision of the side pieces
into separate chambers, which can optionally communi-
cate with each other through openings that can be closed,
it is possible to move the material being milled, as one
chooses, either horizontally or vertically to the next mill-
ing box. Another advantage realized is the control of
the residence time in the mill, thus avoiding hold-up of
material and the formation of dead spaces. By suitably
securing the milling boxes in the side pieces—preferably
with the aid of clamp connections—and by locating the
inlet and outlet openings in the side pieces, the milling
boxes will consist only of plain pipe sections of commer-
cial type, which are readily exchangeable. This obviates,
in many cases, the use of special protective measures
against wear and tear. The boxes may be turned as
desired so that the wear and tear is distributed over the
whole circumference, thereby materially prolonging the
useful life of the mill. If sleeved springs of a resilient
material are used for supporting the milling boxes it is
possible to provide not only a large clamping connection
without tolerance limitations but, in addition to this, a
vibratable multimass system wherein one mass is divided
into several single masses. By appropriate adjustment
of the sleeved springs there is created a vibrating system
that can work in resonance in which the required vibra-
tion generating forces and, therefore, also the load ranges,
are smaller than in the case of a single-mass system. The
resilient sleeved springs permit the subsequent building-in
of cooling jackets for the milling boxes; as they are cap-
able of preventing the escape, not only of the material
being milled, but also of cooling fluid. All parts are
easily interchangeable.

The installation of friction bearings of special design
makes it possible to construct vibratory mills of larger
dimensions operating at higher speeds of oscillation and
having a substantially increased working life. The eccen-
tricities required for creating the centrifugal force are
installed only upon completion of the construction in the
generator shaft which is in the form of a tubular shaft,
thus permitting a lowering of the construction costs. The
cylindrical form of the generator shaft, moreover, reduces
the air resistance and consequently the propulsive output.

The following description sets forth an embodiment of
the invention with reference to the accompanying draw-
ings in which:

FIG. 1 is a sectional view taken through the milling
boxes and the means for generating the vibrating motion
of the mill;

FIG. 2 shows a transverse section through the side
pieces of the mill, and

FIG. 3 shows one exemplified embodiment of the sup-
porting system for the milling boxes.

In FIGS. 1 and 2 there is shown a diagrammatic view
of a continuously operated vibratory mill having 4 milling
boxes. Two box-like side pieces 1 and 2 are rigidly con-
nected with one another by means of a central pipe 3.

They are mounted on a base with the aid of supporting springs 4. The side pieces are divided into separate chambers by partition walls 5 to 8, said chambers being in communication with each other upon removal of the covers 9. The side pieces are provided with inlet openings 10 and outlet openings 11. The milling boxes 13 are inserted through the installation opening 12. The mounting support is provided by sleeved springs 14 which are modified by the box covers 15 and by the tightening of the movable flange 16 in such a way that aside from forming a seal that is airtight and impervious to dust there is insured a sufficiently rigid connection between the milling boxes and the side pieces. The lower part of box covers 15 are grate-shaped. The upper part of the covers are provided with charging ports 18 that are closed by covers 17.

The tubular shaft 19, which is installed in the central pipe 3, is driven by a motor (not shown) through a coupling 20. The shaft turns in friction bearings 21 which are preferably in the form of hydrodynamically lubricated multi-surface friction bearings. The shaft itself is fashioned as a tubular shaft wherein the cylindrical hollow space 22 is subdivided by a longitudinal partition wall 23. One half of the hollow interior is filled with a specifically heavy substance 24 that serves as the eccentric weight.

The milling boxes 13 are filled with auxiliary grinding bodies such as balls or the like through charge ports 18. The admission of the material to be milled is effected selectively through feed pipe 10 emptying in the first closed chamber and from the latter through openings in the lower part of box cover 15 into the first milling box. The material to be milled travels through the box in a horizontal direction and arrives from the chamber located at the end into the next chamber beneath or adjacent it, from where it continues in its transit to the next milling box. The material undergoing milling can either traverse consecutively all the milling boxes or only those that are superposed, which makes it possible, in the case of a multiple feed of material, to form milling groups working in parallel relationship which milling paths are shortened and the output is increased. Thus, the mill is capable of meeting, better than with the means heretofore available, the requirements with respect to fineness and output.

FIG. 3 shows in section a further advantageous form of a mounting support for the milling boxes. Between the milling boxes 13 and the flanges 25 and 26, on the one hand, and the box cover 15, on the other hand, there are provided spacings 27 or 28. By prestressing the flanges 25 and 26, which are suitably displaceable with respect to each other, the sleeved spring 14 encloses the milling box with an initial stress such that the box is able to vibrate in a direction transverse to its longitudinal axis.

The centrifugal force of generator 19 compels the side pieces that are connected by the central pipe to describe gyroscopic vibrations which are transferred by the sleeved springs 14 to the milling boxes 13. In the vibrating multi-mass system, upon suitable adjustment of the operating frequency to the inherent frequency of the system, the oscillation amplitudes of the milling boxes will be greater than those of the generator means.

Two each of oppositely positioned flanges 25 may, if necessary, be connected together by means of a tubular shell 29. This forms a cooling space 30 which is closed by the double-acting sleeved springs 14. As a result of this it is possible to provide a high degree of cooling of the milling box, whereby the heat transfer is not impeded by protective means against wear and tear.

What is claimed is:

1. A vibrating mill including a plurality of generally parallel milling boxes arranged concentrically about a central axis, two end frames, the ends of the said milling boxes being positioned in and carried by the two said end frames, each end frame having a plurality of compart-

ments therein, each compartment being in communication with a single one of the said plurality of milling boxes, and selectively in communication with each other, whereby the material milled can be selectively conducted to a neighboring milling box, such that the residence time of the material in the milling boxes can be chosen on the basis of the ultimate fineness desired, at least one inlet orifice on at least one end frame communicating with one of the said compartments, at least one outlet orifice on at least one end frame communicating with another of said compartments.

5 2. The vibrating mill of claim 1, wherein said compartments are box-like and are defined by walls within said end frame, said walls having parts therein selectively operable and closable to thereby establish communication between adjacent compartments.

15 3. The vibrating mill of claim 1, wherein the said milling boxes are tubular with the longitudinal axes of the tubular boxes being parallel to the said central axis.

20 4. The vibrating mill of claim 1, wherein the ends of the said milling boxes are held by a clamping connection providing a resilient gas and liquid impervious joint between the milling boxes and the compartments with which they communicate.

25 5. The vibratory mill of claim 4, wherein the clamping connection is effected by means of a resilient circumferential ring.

30 6. The vibratory mill of claim 1, including resilient circumferential means for holding the ends of the said milling boxes and permitting rotating of the boxes about their lengthwise direction.

35 7. The vibratory mill of claim 1, wherein the end of each milling box is closed by end pieces, each end piece having a grate at the lower portion thereof and having a selectively openable and closable aperture at the upper portion.

40 8. The vibratory mill of claim 1, including energizable means carried by the mill for vibrating it in directions transverse to the said central axis.

45 9. The vibratory mill of claim 8, wherein the said energizable means comprises an elongated and rotatable cylinder extending between the end frames and mounted on a shaft, the said shaft journaled on bearings, the said bearings being connected to the said end frames, the said cylinder being divided by a partition thus defining a closed volume within the said cylinder, the said closed volume being eccentrically located with respect to the said central axis and containing a heavy mass that serves as the eccentric weight.

50 10. The vibratory mill of claim 9, wherein the said bearings are hydro-dynamically lubricated multi-surface friction bearings which are lubricated by constant circulation oiling.

55 11. The vibratory mill of claim 1, wherein the end frames are compartmentwise symmetrical.

12. The vibratory mill of claim 1, wherein at least one of the said milling boxes is at least partially surrounded by a jacket spaced from the exterior surfaces thereof to define a chamber for the introduction of a coolant.

60 13. The vibratory mill of claim 8, wherein said energizable means is a hollow shaft subdivided by a wall, such that substantially one half of the hollow space is filled with a mass serving as an eccentric weight.

65 14. The vibrating mill of claim 1, wherein said plurality of milling boxes is comprised of a first upper group and a second lower group, at least one end frame having a said inlet orifice for each of said compartments communicating with one of said milling boxes of said upper group, and at least one end frame having a said outlet orifice for each of said compartments communicating with one of said milling boxes of said lower group.

70 15. The vibrating mill of claim 1, wherein said plurality of milling boxes is comprised of a first upper group and a second lower group, each of said end frames having a said inlet orifice for each of said compartments com-

municating with one of said milling boxes of said upper group, and each of said end frames having a said outlet orifice for each of said compartments communicating with one of said milling boxes of said lower group.

16. The vibrating mill of claim 3, including resilient circumferential means for holding the ends of said milling boxes, and said milling boxes being tubular, whereby the cooperation between said resilient means and the tubular shape of said boxes permits readily substituting one box for another.
